BATHTUB HEADREST

Billy Erik Olsson, Chicago, Ill.

Application December 20, 1955, Serial No. 554,187

7 Claims. (Cl. 4—185)

This invention relates to a headrest for use in connection with a bathtub whereby a bather's head may be supported in a comfortable position while the bather lies relaxed in the tub.

One of the primary purposes of my present invention is to provide a head rest of the character indicated which can be readily adjusted as to height and as to position longitudinally of the tub and which will be so suspended as to automatically adjust itself to various positions which the head of the bather may assume so as to thereby afford a rest which will conform to the head position and provide maximum comfort for the user.

Another object of the invention is to provide a head rest which may folded up against the wall entirely outside the confines of the tub where it will not interfere with cleaning of the tub or with a bather taking a shower bath therein.

Another object is to provide a head rest which can be easily assembled and disassembled, permitting the flexible head support to be detached from the supporting arms whenever desired and which can be readily adjusted to various positions and which by reason of universal mounting of the support will automatically accommodate itself to the position of a bather's head.

Other objects and advantages of my invention should be readily apparent as the same becomes better understood by reference to the following description when considered in connection with the accompanying drawing.

Referring to the drawing,

Figure 1 is a fragmentary perspective view showing my novel headrest positioned for use;

Fig. 2 is a fragmentary plan view on an enlarged scale of one of the supporting arms and connected parts;

Fig. 3 is a sectional view on the line 3—3 of Fig. 2;

Fig. 4 is a fragmentary sectional view on the line 4—4 of Fig. 2; and

Fig. 5 is an elevation of one of the brackets, certain parts being shown in section.

Referring now to the drawings more in detail, reference character 6 indicates a bathtub of conventional or preferred design at the head end of which it is proposed to install my improved headrest.

It will be observed that the rest is not attached directly to the tub, but is supported from the head wall 7 upon which a pair of brackets indicated generally by reference character 8 is mounted by means of conventional screws or bolts (not shown). Each bracket comprises a base 9 and an arm 11 pivotally supported at one end on the base by a pintle 12. The arms 11, by reason of the pivotal mounting, may be swung upwardly into substantially vertical position against the face of the end wall so as to be entirely clear of the tub where they will offer no interference with cleaning of the tub or with a shower bather standing therein.

Each arm 11 is vertically adjustable and is supported in different adjusted positions by a dog 13 urged by a spring 14 into engagement with one of the shoulders 15 formed in the base 9. Handles or grips 16 may be em-

ployed to withdraw the dogs 13 from holding position to enable the arms 11 to be lowered when desired.

Each arm 11 is also provided on its top face with a plurality of spaced apart grooves 17 and is provided on its outer face with a longitudinally extending groove 18 forming overhanging lips 19 between the grooves 17 beneath which a longitudinally extending portion 21 of a bifurcated link 22 is engaged. This link, which may be formed of wire of suitable size and strength, is curled at its free ends to form a pair of eyes 23 in which is rotatably mounted a member 24 extending substantially parallel with the adjacent arm and adapted to partake of rotative or oscillatory movements about its longitudinal axis.

Each member 24 is provided with a transversely extending opening 25 in which is disposed the eye 26 of a bolt 27, the bolt being pivotally secured in the member 24 by a pin 28 about which the bolt may swing longitudinally of the member. Rotative movement of the members 24 in the links 22, together with the swinging movements of the bolts 27 about the pins 28 affords a universal automatically adjustable support for the headrest.

The bolts 27 are threaded through the head blocks 29 disposed in parallelism with the members 24. The threaded engagement serves to adjustably hold the blocks 29 on the bolts whereby the blocks are swiveled so as to tilt on the bolts.

The head support consists primarily of a web or strip 32 of flexible material, such as canvas or the like, upon which the head may be supported and, if preferred, a pad 33 of sponge rubber or other suitable padding material may be applied to the upper face thereof to provide greater comfort for the user. The ends of the support 32 are wrapped around and clamped to the head blocks 29 by plates 31 secured to the blocks by screws 30. The support is thus suspended between the arms 11 and its curvature may be varied by adjusting the position of the head blocks on the bolts 27.

From the foregoing it should be apparent that I have provided a head rest for bathtubs which is capable of universal adjustment and also capable of automatic conformation to the position of the bather's head. The arms 11 of the brackets may be adjusted to any vertical height, and the links 22 carried by the arms 11 may be adjusted longitudinally of said arms by disconnecting them from the lips 19 and positioning them in others of grooves 17. The members 24 are rotatable in the links and the bolts 27 may be swung lengthwise of the arms about the pins 28. Finally, the head blocks 29 are capable of tilting about the axis of the bolts and the position of the blocks longitudinally of the bolts may be varied by adjusting the blocks longitudinally of the bolts.

A universal adjustment of the position of the support 32 is accordingly provided, so that the utmost comfort to the user of the headrest is afforded.

Obviously the structural details illustrated and described may be varied within considerable limits without departing from the scope of the invention as defined in the following claims.

I claim:

1. A bathtub headrest, comprising a pair of brackets constructed to be mounted above the head of a bathtub and to project longitudinally of the tub in spaced apart relation, each bracket including a base, an arm pivotally mounted thereon so that the free end thereof may be vertically adjusted and means for holding said arm in adjusted position, a member disposed parallel to each of said arms and rotatably connected thereto, a bolt pivoted on each of said members to swing in an arc longitudinally of said member, a head block carried by each of said bolts, said blocks being adjustable longitudinally of said

bolts and being free to tilt about the longitudinal axes of said bolts, and a head support suspended from and between said blocks so as to automatically conform to various positions of the bather's head.

2. A bathtub headrest, comprising a pair of spaced apart wall brackets each consisting of a base and a supporting arm adjustably mounted thereon, a member disposed in substantial parallelism with each of said arms, means whereby said members are rotatably supported from said arms to rotate about axes substantially parallel with said arms, a bolt pivoted at one end to each of said members so as to permit the free end thereof to swing longitudinally of said member, a head block pivotally mounted on each of said bolts and a flexible head support suspended between said blocks.

3. A bathtub headrest, comprising a pair of spaced apart wall brackets each including a base, an arm pivoted thereon and means for supporting said arm in adjusted position, a flexible head support suspended between said arms, and means including a pair of rotatable members, a bolt pivoted on each member and a head block pivotally mounted on each bolt, whereby said support is suspended so as to be capable of universal adjustment to conform to the position of the head of a user.

4. The headrest defined in claim 3, in which the bracket bases are provided with abutment shoulders and the supporting arms are provided with spring biased dogs arranged to engage said shoulders for supporting said arms in adjusted positions.

5. The headrest defined in claim 3, in which said rotatable members are supported from said arms by links rotatably supporting said members and detachably connected to said arms.

6. The headrest defined in claim 5, in which means connect said supporting links to said arms for adjustment longitudinally of said arms to vary the position of the headrest longitudinally of a tub.

7. The headrest defined in claim 6, in which said arms are provided with a longitudinal groove and a plurality of transverse grooves spaced apart and communicating with said longitudinal groove, and a link constructed and arranged to be adjustably engaged in said grooves for supporting the head rest in various positions.
